UNITED STATES PATENT OFFICE.

SAMUEL F. KING, OF BIRMINGHAM, ALABAMA.

SAND-MOLDING APPARATUS.

Application filed August 6, 1923. Serial No. 656,060.

To all whom it may concern:

Be it known that I, SAMUEL F. KING, a citizen of the United States of America, residing at Birmingham, in the county of Jefferson and State of Alabama, have invented certain new and useful Improvements in Sand-Molding Apparatus, of which the following is a specification.

My invention relates to improvements in molding apparatus especially adapted for the casting of hollow articles such as pipes, radiators and the like, and it contemplates the provision of means which will dispense with hand ramming and which will make use of mechanism to squeeze or pack the sand about the patterns and core prints in the manner calculated to produce the requisite density or firmness of the sand without interfering with the proper venting of the mold.

More particularly my invention contemplates the utilization of a sand squeezing machine adapted to receive the inverted cope or drag and having independently movable stripping plates and patterns, my improved operation contemplating squeezing the sand in the flask first by movement of the stripping plate relatively to the patterns, and then completing the squeezing operation by moving the stripping plate and patterns together, and finally by lowering the patterns relatively to the stripping plate to strip them from the sand mold.

It will be noted that the joint movement of the stripping plate and patterns which continues the conclusion of the squeezing operation avoids the breaking of the sand mold which would occur if relative movement were permitted between the stripping plate and patterns after either had reached its final position.

An important feature of my invention is the mounting of the core prints for the patterns when used on the stripping plate so that it is only the patterns proper that move independently of the stripping plate.

My invention also contemplates the provision of means readily adapted to adjust the operating position of the patterns and the lowered position of the stripping plate

relatively to the patterns, said adjustments making it possible to accurately match the plate and patterns for different adjustments which determine the amount of loose sand used and the degree of its compression.

55

My invention also contemplates the novel idea of adapting the tumbling bars controlling the receding movement of the patterns to be engaged by the rising stripping plate at any predetermined point so as to pick up and move the patterns with the plate.

60

My invention also contemplates an improvement in the forming of the pouring gates by the use of downwardly tapering gate pins which extend to the parting line, it being possible to use such taper pins by reason of the fact that the sand is squeezed towards the larger end of the pin, thus making it possible to draw it and avoiding the necessity of enlarging the present gate holes formed by straight gate pins.

65

My invention further comprises the novel details of construction and arrangements of parts, which in their preferred embodiment only are illustrated in the accompanying drawings, which form a part of this specification, and in which:

75

Fig. 1 is a side elevation; and

Fig. 2 is a plan view of my sand molding machine.

Fig. 3 is an end view; and

Fig. 4 is a cross-sectional view taken on the line 4—4 of Fig. 1.

Figs. 5, 6, 7 and 8 are cross-sectional views corresponding to Fig. 4, showing the cope or drag assembled on the molding machine and illustrating the various operations incidental to forming the mold.

85

Fig. 9 shows the complete mold; and

Figs. 10 and 11 show the complete drag and cope, respectively.

Similar reference numerals refer to similar parts throughout the drawings.

95

I have illustrated my invention as applied to the manufacture of soil pipe, though the pattern design may obviously be changed for the molding of any cast article. In the drawings I have shown the apparatus adapted to form molds for a short

100

length soil pipe which will serve for illustrative purposes. My molding apparatus comprises a rectangular frame 1 open top and bottom and having vertically movable 5 therein an inverted box-like plunger or squeezer member 2 open underneath and having a longitudinal vertical central partition 3 and a top plate 4 which forms the stripping plate of the apparatus. The plunger works with a close sliding fit in the frame and has formed in its top plate 4 openings 5 through which a pair of pipe patterns 6 project. These patterns are shown with straight deep parallel sides 15 which are slidingly engaged by the marginal side walls of the openings 5 which conform thereto. The plate 4 also carries at each end core prints 7 and 8 which are fast thereon and are not attached to the pipe patterns 6 as is customary.

The patterns 6 are supported by two or more tumbling bars 9 having pattern supporting cam members 10 thereon and these tumbling bars are mounted in vertically 25 elongated slots 11 in the side walls and central partition 3 of the plunger. The ends of the tumbling bars project through vertical elongated slots 12 in the sides of the frame 1 and are adapted at each end to be 30 engaged by a pair of independently adjustable stop plates 13 and 14 adjustably connected by set screws 15 to the side of the frame. These stop plates may be adjusted to limit the vertical movements of the tumbling bars. A crank handle 17 is fast on one tumbling bar and is connected by a link 18 to a crank 19 fast on the other tumbling bar so as to move the two in unison. The plunger 2 has at the center of each end an 35 elongated block 20 which slides in a slot 21 in the frame. A boss 22 at the upper end of each slide block projects beyond the end wall of the frame and carries a stud or pin 23 to which is connected the upper end 40 of an operating rod 24 having therein a turn buckle 25 for purposes of adjusting its length. This operating rod at its lower end is connected to a crank 26 fast on a cross bar or shaft 27 extending lengthwise through and journaled in the lower rear portion of the frame 1. The plunger 2 is slotted or cut away at 28 to pass the same. The cranks 26 have sockets 29 which receive operating handles 30. The slots 21 extend almost to the 45 top of the frame, thus permitting the slide blocks 20 and studs 22 to ride upwardly when the levers 30 are depressed so as to lift the plunger 2 and with it the stripping plate 4 and patterns 6 in the manner which 50 will now be described.

In operating my invention I first place a drag 31 mounted with its larger part downward on the frame and suitably clamp it thereto by clamping and matching means 55 not shown. The tumbling bars are set to

raise the patterns, and the levers 30 are raised by the weight of the plunger 2 which stands with its stripping plate in its lowermost position. Loose sand is then introduced to fill the frame and drag and a top 70 plate 32 is suitably clamped to the drag. The apparatus is now with its parts in the position shown in Fig. 5 and is ready for the squeezing operation which is accomplished entirely by the operation of the levers 30 or 75 equivalent power means to move the plunger 2, and which produces the following sequence of events.

First, through the rods 24 and studs 22 the plunger carrying the stripping plate and core prints alone are raised, thus effecting the initial or partial squeezing of the sand round the margins of the patterns and the core prints but not over the patterns proper. At the completion of this initial squeezing 85 operation, the parts stand as shown in Fig. 6, which shows that the plunger has been raised until the lower ends of the slots 11 therein engage and pick up the tumbling bars 9, whereupon the further raising of the 90 stripping plate will carry with it the tumbling bars and the patterns to the position shown in Fig. 7 when the drag is finished. The next operation, as shown in Fig. 8, is to move the crank handle 17 and cause the 95 patterns to recede from the sand mold, after which the finished drag can be lifted off and the cope 33 mounted and squeezed. When the cope is rammed taper gate pins 34 are provided with their larger ends uppermost 100 and mounted by inserting their lower ends in the holes 35 in the stripping plate so that by lifting off the plate 32, a completely finished taper gate hole 36 is formed in the sand, as shown in Fig. 11, and adapted to 105 register with the gate 37 formed in the usual manner in the drag mold. It will thus be seen that the entire operation is carried out mechanically and without requiring expert labor or any hand work except the manipulation of the levers 30 and the drawing of the gate 34.

By adjusting the plates 14 and 15 the upper and lower limits of movement of the tumbling bars can be controlled and consequently the raised and lowered positions of the patterns. It being understood that the downward movement of the plunger 2 is limited by the cranks 26 striking the stops 38 on the frame, it follows that by manipulating the turn buckles 25 the plunger 2 and stripping plate 4 can be adjusted relatively to the patterns so that the latter will accurately match the patterns whatever their adjustments. Obviously, by raising or lowering the patterns the amount of sand above them is varied and its density in the finished mold controlled. It is important to note that in my operation the sand about the edges of the prints and the patterns, but not 115 120 125 130

over the patterns, is squeezed to a considerable degree before any pressure at all is applied to the sand immediately above the patterns proper. This results in very sharp firm surfaces where the molds meet and forms hard prints and light compression of the sand above and below the complete mold proper. This is ideal in that it reduces fins and run outs to the maximum extent possible and leaves a sand mold which will vent freely.

I claim as a distinctive feature of my invention the squeezing of the sand toward the smaller part of the flask element (cope or drag), preferably using a movable stripping plate to do the work. The advantages are obvious, I can use a shallower flask element free of sand strips and therefore less sand; I can press the sand tightly against the flask walls as they converge so that it will not break out; I can use bars in the flask to more firmly hold the sand; and by compressing the marginal edges of the sand against converging and not diverging flask walls I get the desired compactness about the mold cavity which it has been very hard to get where the sand is rammed towards the larger part of the flask.

Though I have described with great particularity the details of the embodiment of the invention herein shown, it is not to be construed that I am limited thereto, as changes in arrangement and substitution of equivalents may be made by those skilled in the art without departing from the invention as defined in the appended claims.

What I claim as new and desire to secure by Letters Patent, is:—

1. A sand mold apparatus, comprising a frame, a flask element mounted thereon, a stripping plate and pattern mounted in the frame free to move towards said flask element, core prints for the pattern mounted on the stripping plate, and means to squeeze sand into said flask element first by the movement of the stripping plate only, and lastly by joint movement of stripping plate and patterns.

2. A sand mold apparatus, comprising a frame, a flask element mounted thereon, a stripping plate and pattern mounted in the frame free to move independently towards said flask element, and means to squeeze sand into said flask element first by a movement of the stripping plate only, and then by a joint and equal movement of stripping plate and patterns.

3. A molding apparatus in accordance with claim 2, in which the means to squeeze the sand in the flask is adapted to pick up and move both stripping plate and patterns jointly and equally throughout the conclusion of the squeezing operation.

4. In a molding apparatus, in combination, a frame adapted to receive a flask ele-

ment, a stripping plate adapted to recede into said frame and means to raise it, patterns adapted to recede into said frame and means to raise and lower them, and means operable at a predetermined point in the lifting movement of the stripping plate to cause the stripping plate and pattern to move in unison.

5. A molding apparatus in accordance with claim 4, in which the means for raising and lowering the patterns are tumbling bars which have a lost-motion connection with said stripping plate.

6. In a molding apparatus, a frame adapted to receive a flask element, a stripping plate adapted to recede into the frame, means to raise said stripping plate to squeeze sand into the flask element, patterns relative to which said stripping plate is movable, tumbling bars for the patterns, and means to establish a lost-motion operating connection between the stripping plate and tumbling bars.

7. A molding apparatus in accordance with claim 6, in which the frame is provided with vertically elongated slots through which the tumbling bars pass.

8. A molding apparatus in accordance with claim 6, in which the stripping plate has depending side members, there being aligning vertically elongated slots in said members and frame through which said tumbling bars project.

9. A molding apparatus in accordance with claim 6, in which the frame has vertically elongated slots through which the tumbling bars pass, and adjustable stop means to limit the movement of said tumbling bars.

10. In a sand molding apparatus, a frame adapted to receive a flask element, a stripping plate vertically movable in the frame, operating means to raise said plate and squeeze sand in the flask element, patterns having straight sides, tumbling bars supporting said patterns in the frame, there being slots in the frame to permit the tumbling bars to rise with the patterns, means movable with the stripping plate to pick up the tumbling bars and carry the patterns with them, and means to adjust the operating means to cause the stripping plate to match the patterns in operating position.

11. In a sand molding apparatus, a frame adapted to receive a flask element, a stripping plate vertically movable in the frame, operating means to raise said plate and squeeze sand in the flask element, patterns having straight sides, tumbling bars supporting said patterns in the frame, there being slots in the frame to permit the tumbling bars to rise with the patterns, means movable with the stripping plate to pick up and carry the patterns with them, means to adjust the operating means to cause the stripping plate

to match the patterns in operating position, and means to adjust the operating position of the patterns.

12. In a molding apparatus, a stripping plate plunger movable to squeeze sand in a flask, a pattern movable to co-operate with the plunger, core prints, and means to move

said prints independently of the pattern to squeeze the sand about them more tightly than it is squeezed by the patterns.

In testimony whereof I affix my signature.

SAMUEL F. KING.
